A. L. SOHM

RADIATOR LOCKING CAP

Filed May 18, 1925

Inventor
Alfred L. Sohm,

Attorney

UNITED STATES PATENT OFFICE.

ALFRED L. SOHM, OF CHICAGO, ILLINOIS.

RADIATOR-LOCKING CAP.

Application filed May 18, 1925. Serial No. 31,153.

To all whom it may concern:

Be it known that I, ALFRED L. SOHM, a citizen of the United States, residing at Chicago, in the county of Cook and State of Illinois, have invented certain new and useful Improvements in Radiator-Locking Caps, of which the following is a specification.

This invention relates to radiator locking caps and more particularly to a cap adapted to support a radiator ornament, signal or the like and provided with a manually controlled means for locking it securely to a radiator spout to prevent its unauthorized removal.

An important object of the invention is to provide a plurality of gripping members adapted to be manually moved outwardly into engagement with the filling spout of an automobile radiator and provided with means to prevent their withdrawal.

A further object is to provide a device of the above mentioned character which is adapted for use on radiator spouts of varying diameters, the locking means employed being adapted upon operation to properly center the cap over the radiator spout.

Other objects and advantages of the invention will be apparent during the course of the following description.

In the drawings I have shown one embodiment of the invention. In this showing:

Figure 1 is a central vertical sectional view through the device in place on a radiator spout, parts being shown in elevation,

Figure 2 is a plan view of the device with the radiator signal removed,

Figure 3 is a bottom plan of the device with the locking sleeve and associated elements removed, parts being broken away, and

Figure 4 is a section taken on line 4—4 of Figure 1.

Referring to the drawings, the numeral 10 designates an ordinary automobile radiator filling spout through which water is introduced in filling the radiator. The device forming the subject matter of the present invention comprises generally a cap 11 provided with a substantially cylindrical central portion 12 having an opening 13 therein. In the present instance the opening 13 is shown as being of materially greater diameter than the filling spout and it will be apparent that the device is adapted to

be employed in connection with filling spouts of various sizes. The cap 11 may be provided with ornamental arms 14 or any other suitable ornamentation which may be desired. A gasket 15 is arranged in the upper end of the opening 13 and is adapted to engage the upper end of the filling spout to provide a leak-proof joint.

The cap 11 is provided in its upper end with an opening 16 of smaller diameter than the opening 13 as shown. The upper face of the cap is provided outwardly of the opening 16 with an annular recess 17 in which is mounted a rubber or similar gasket 18. A collar 19 is adapted to be arranged over the cap in contact with the gasket 18, as shown. The cap is provided preferably at its rear side with ears 20 between which is arranged a boss 21 formed integral with the collar 19. A pivot pin 22 passes through the boss 21 and ears 20 to pivotally connect these members. A locking member 23 is pivotally connected as at 24 to the forward side of the cap and is provided at its upper end with a horizontal lip 25 overhanging a lug 26 formed integral with the collar 19. A thumb screw 27 is carried by the lip 25 and is adapted to be clamped downwardly against the lug 26. It will be apparent that when the screw 27 is loosened the upper end of the locking member may be swung outwardly to permit the forward portion of the collar 19 to be lifted. The locking member 23 is adapted to maintain the collar 19 tightly seated against the gasket 18 to prevent leakage between the collar and the upper end of the cap 11. The means for pivotally connecting the collar 19 to the cap and clamping it thereto are shown in detail in my prior Patent No. 1,541,073, dated June 9th, 1925.

As shown in Figures 1 and 2, the collar 19 is provided with an annular depression 28 and a central opening 29 through which vapors and steam from the radiator are adapted to pass. In my prior patent above identified, I have shown and described a radiator signal which is adapted to be mounted within the recess 28. The signal may include a cylinder 30 adapted to be pressed within the recess 28 and provided with a vertically movable cap 31 which is adapted to warn the operator of the vehicle when excessive pressure is present in the radiator.

The cap 11 is provided within the opening 110

16 with preferably integral inwardly and downwardly extending radial arms 32 terminating at their inner ends in a cylindrical portion 33. A screw 34 is mounted to rotate in the cylindrical portion 33 and is provided at its upper end with a head 35 having a screw driver slot 36 therein to permit its manual rotation. As shown in Figures 1 and 3, the cylindrical portion 33 is provided in its lower end with a circular recess 37 in which is arranged a ratchet wheel 38 connected to the screw 34 by a pin 39 whereby it is adapted to rotate therewith. An arcuate leaf spring 40 is arranged outwardly of and in contact with the cylindrical portion 33 and is connected at one end thereto by a screw or pin 41. A ratchet tooth 42 is secured to the opposite end of the spring 40 and extends inwardly through an opening 43 formed in the cylindrical portion 33. The inner end of the tooth 42 is adapted to engage the teeth of the wheel 38, as clearly shown in Figure 3.

A sleeve 44 is arranged below the ratchet wheel and is internally threaded to receive the screw 34. The sleeve 44 is provided with pairs of spaced ears 45 between which are mounted the inner ends of gripping members 46. The gripping members are pivotally connected to the ears by pins 47. The pins 47 and the ears 45 are adapted to snugly fit the gripping members 46 whereby the latter will be retained in the vertical or dotted line position indicated in Figure 1 when the sleeve is inserted within the filling spout, as will be understood. The outer ends of the gripping members are provided with gripping edges 48 adapted to tightly grip against the inner face of the filling spout as shown in Figures 1 and 4. The cylindrical portion 33 is provided with a depending and outwardly extending lug 49 which is adapted to engage against one of the gripping members 46, as shown in Figure 4.

The operation of the device is as follows: The collar is arranged in the position shown in dotted lines in Figure 1 with the gripping members 46 projecting vertically. The signal 30 and collar 19 are then swung about the hinge pin 32 to provide access to the interior of the cap 11. The device is then placed in position over the filling spout of the radiator with the upper end thereof in contact with the gasket 15. The end of the screw driver is then inserted within the slot 36 and the screw 34 revolved. Contact of the lug 49 with one of the gripping members 46 prevents rotation of the sleeve 44, as will be obvious. Since the sleeve is prevented from rotating, it will be obvious that rotation of the screw in a clockwise direction will cause the sleeve 44 to move upwardly. The gripping members will contact with the lower end of the cylindrical portion 33 and the upper ends of the grip-

ping members will be caused to move outwardly. Continued rotation of the screw is adapted to cause the gripping edges 48 of the members 46 to tightly engage against the inner surface of the filling spout and since these gripping members are concentrically placed, it will be obvious that they serve to center the cap over the filling spout. As the screw is revolved in the manner described, it will be apparent that the ratchet wheel 38 also will be revolved and the tooth 42 will escape over the ends of successive teeth of the ratchet wheel by moving outwardly against the tension of the spring 40. After the gripping members have been tightly engaged against the inner surface of the filling spout, it will be obvious that reverse rotation of the screw will be prevented by the engagement of the ratchet tooth with the teeth of the ratchet wheel, thus preventing unauthorized removal of the cap.

It is to be understood that the form of my invention herewith shown and described is to be taken as a preferred example of the same and that various changes in the shape, size and arrangement of parts may be resorted to without departing from the spirit of the invention or the scope of the subjoined claims.

I claim:

1. A device of the character described comprising a cap having an open lower end adapted to receive the upper end of the filling spout of an automobile radiator, a sleeve arranged in said cap and movable parallel to the axis thereof, a plurality of gripping members pivotally connected at their inner ends to said sleeve, means for turning the free ends of said members outwardly into engagement with the filling spout when said sleeve is moved, an axial screw engaging said sleeve and rotatable in one direction to effect movement of said sleeve, and means for preventing reverse rotation of said screw.

2. A device of the character described comprising a cap having an open lower end adapted to receive the upper end of the filling spout of an automobile radiator, an axial bearing arranged in said cap; an axial screw rotatably mounted in said bearing, a sleeve threaded on said screw, a plurality of substantially radial gripping members pivotally connected at their inner ends to swing vertically, and means for preventing rotation of said sleeve, a portion of said bearing being adapted to contact with said gripping members to turn the free ends thereof outwardly into engagement with the filling spout when said screw is rotated in one direction.

3. A device constructed in accordance with claim 2 provided with means for preventing reverse rotation of said screw.

4. A device constructed in accordance

with claim 2 provided with a ratchet wheel secured to said screw to rotate therewith, and a ratchet tooth engaging said wheel.

5. A device constructed in accordance with claim 2 provided with a ratchet wheel secured to said screw to rotate therewith, an arcuate leaf spring partially surrounding said bearing and secured at one end thereto, and a ratchet tooth carried by the opposite 10 end of said spring and adapted to engage said ratchet wheel.

6. A device of the character described comprising a cap adapted to be arranged over the filling spout of an automobile radia-

tor, a member arranged in said cap and 15 movable parallel to the axis thereof, a plurality of gripping members pivotally connected at one end to said movable member, means for turning the free ends of said members outwardly into engagement with the filling spout when said movable member is moved in one direction, a rotatable screw 20 threaded in said movable member, and means associated with said screw for preventing rotation thereof in one direction. 25

In testimony whereof I affix my signature,

ALFRED L. SOHM.
